CLAIM

The ornamental design for an accessory chain, as shown and described.

DESCRIPTION

FIG. 1 is a perspective view of the accessory chain; FIG. 2 is a front elevational view thereof, the rear elevational view (not provided) being a mirror image of the front elevational view;

FIG. 3 is a left-side elevational view thereof;

FIG. 4 is a right-side elevational view thereof; and,

FIG. 5 is a top plan view thereof, the bottom plan view (not provided) being a mirror image of the top plan view.

The dashed broken and jagged break lines define the bounds of the claimed design and form no part thereof. The appear-

(Continued)

ance of any portion of the article between the jagged break lines forms no part of the claimed design.

1 Claim, 2 Drawing Sheets
